UNITED STATES PATENT OFFICE.

EDWARD F. BROWN, OF JOHNSTON, AND JAMES E. REED, OF NORTH PROVIDENCE, RHODE ISLAND.

DESIGN FOR A RADIATOR-CORE.

56,735.

Specification for Design.

Patented Dec. 14, 1920.

Application filed October 13, 1919. Serial No. 330,491. Term of patent 14 years.

To all whom it may concern:

Be it known that we, EDWARD F. BROWN and JAMES E. REED, both citizens of the United States, residing at Johnston and North Providence, respectively, in the county of Providence and State of Rhode Island, have invented a certain new, original, and ornamental Design for a Radiator-Core, of which the following is a specification.

In the accompanying drawings which form a part of this specification the figure is a front elevation of a radiator core embodying our new design.

We claim:

The ornamental design for a radiator core substantially as shown.

EDWARD F. BROWN.
JAMES E. REED.
